(57) CLAIM

The ornamental design for a purse organizer, as shown and described.

DESCRIPTION

FIG. 1 is a perspective view of the purse organizer showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines shown in the drawings are included for the purpose of illustrating portions of the purse organizer that form no part of the claimed design.

1 Claim, 8 Drawing Sheets
